UNITED STATES PATENT OFFICE.

CHARLES H. NORTH, OF CLEVELAND, OHIO, ASSIGNOR, BY MESNE ASSIGNMENTS, TO
FREDERICK C. STEVENS, OF ATTICA, NEW YORK.

TELEPHONE-EXCHANGE APPARATUS.

1,130,190.

Specification of Letters Patent.

Patented Mar. 2, 1915.

Application filed April 4, 1911. Serial No. 618,829.

To all whom it may concern:

Be it known that I, CHARLES H. NORTH, a citizen of the United States, residing at Cleveland, in the county of Cuyahoga and 5 State of Ohio, have invented certain new and useful Improvements in Telephone-Exchange Apparatus, of which the following is a specification, reference being had therein to the accompanying drawing.

10 My invention relates to telephone exchange apparatus, and has for its object the improvement thereof in divers particulars which will appear hereinafter.

This invention has to do among other 15 things with the method of mounting and arranging switches of the type described and illustrated in my Patent No. 977,536, patented December 6, 1910; and while it relates particularly to the mechanical features 20 of the so-called "Clement-Automanual" exchange systems, it may be usefully employed in connection with any automatic or semi-automatic system to which this type of switch is adaptable.

25 Briefly stated, the invention contemplates the division of the working apparatus in an exchange into self-contained and complete unitary sections, the several parts of which shall be interchangeable, as well as the sections themselves. By this means, a great deal of assembling and wiring work can be done in the factory which has heretofore been deferred until the apparatus has been installed in place. A further and very 35 marked advantage is that in case of accidental destruction of parts, as for example by fire, and in case of increases or additions to the equipment of a working exchange, new sections may be installed without disturbing or rewiring those already in service.

The underlying principle in the entire present case is the provision of interchangeable units to form pieces of apparatus, the assemblage of these pieces of apparatus to 45 form groups, and the disposition of such groups to form complete equipments. The smallest unit group commonly employed in telephone exchanges is one accommodating one hundred lines, and for convenience I have adopted this as my standard group or 50 section of apparatus. It will of course be understood that this may be varied without departing from the scope of the invention.

55 My method of procedure is as follows: I form an individual switch of the following

standard parts which in themselves are interchangeable: contact banks, a spindle with its ratchets and wipers, and one or more working magnets. The spindle is mounted in a frame which also supports the 60 magnet. This frame and the banks are then adapted to a switch plate, and where two or more switches are closely associated with wiring between them, they are mounted on the same plate. To this plate are also 65 attached the controlling relays for the switch or switches, the condensers, if any, which are included in the switch circuits, and any subsidiary parts such as distributing switches which are controlled by the relays 70 and themselves control, or are ancillary to, the main switch. Such a switch plate when wired up becomes a complete connecting unit. A suitable number of these plates being then mounted together upon a common 75 rack form a section, and to the same rack I attach the pilot signals, group relays, guard lamps, cable boxes and other paraphernalia which are common to a section or group 80 of switches. All the local or cross wiring on each section is done in the factory, and said section is boxed and shipped ready to set up in place and operate when the line wires are attached to their terminals.

My invention is illustrated in the accompanying drawings wherein—

Figure 1 is a front view of a mounting plate stripped. Fig. 2 is a section on line a—a of Fig. 1. Fig. 3 is a side view of the same. Fig. 4 is a front view of the same 90 plate with connector switch and its associated parts mounted thereon. Fig. 5 is a side view of the same. Fig. 6 is a similar view of a plate carrying a primary and first selector switch and other associated parts, 95 the lower end of the plate being extended to accommodate the second switch. Fig. 7 is a side view of the same. Fig. 8 is a front view of a complete section comprising a rack carrying ten of the plates shown in Fig. 4, 100 and ten of the plates shown in Fig. 6, together with the line and cut-off relays and auxiliary apparatus sufficient to accommodate one hundred lines. Fig. 9 is a vertical cross section on the line 9—9 of Fig. 8 looking in the direction of the arrows. Fig. 10 is an end view of the same section looking from the left of Fig. 8.

Referring first to Figs. 4 and 5, S designates one form of my switch in its entirety,

with a frame s , which is preferably a finished white metal casting, ready for use when taken from the mold and covered with a thin coating of silver electrolytically deposited. s' is the spindle carrying a pair of insulated wipers s^2 which coöperate with the contacts in the banks s^4 and s^5 . The bank s^4 is not shown in order that the wipers s^2 which coöperate with the bank may appear. 5 The spindle is adjusted to bring the wipers into conjunction with any desired contacts in the banks by means of rotary and vertical ratchets s^6 and s^7 with which engage pawls carried by the armature levers s^8 and s^9 10 which are actuated by the rotary and vertical magnets s^{10} and s^{11} respectively. Further detailed description of this switch is thought to be unnecessary, as in itself it forms no part of the present invention and 15 is fully described and explained in my aforesaid applications. Figs. 4 and 5, however, show the method of mounting the switch upon the plate P which forms the base or support for one of the unitary 20 groups or assemblages of apparatus. This plate is perforated, as will presently appear, at several points, and in the perforations are fixed posts p , p' , etc., drilled and tapped to receive screws in both ends. The 25 banks s^4 and s^5 are attached to the rear face of the plate by means of lugs s^{12} formed on the upper and lower metal plates of the banks. The frame s on the other hand is attached to the front of the plate by means of 30 screws passing through ears s^{14} formed on the frame, and so into the front ends of the posts. The banks and the switch frame being thus attached to the same posts, are closely related, the posts serving as fixed 35 distance pieces, and supporting the other parts on the plate P without danger of displacement or loss of adjustment, whatever variations there may be in the plate.

Referring now to Figs. 1, 2 and 3, I have 40 shown therein the plate P in its simplest form, intended for a connector switch and circuit. It is shown complete with all parts mounted upon it in Figs. 4 and 5, but the shape, openings and posts are best seen in 45 Figs. 1 and 2. The plate is punched and formed up from sheet steel, with parallel ribs p^{20} and p^{21} along its opposite edges to 50 impart stiffness to the body. It has one large opening p^7 , a smaller opening p^8 and 55 other still smaller openings p^9 , p^{10} , p^{11} , p^{12} , p^{13} , p^{14} and p^{15} besides a considerable number of holes punched for the attaching 60 screws of relays, and those for the posts p to p^6 inclusive. Notches p^{16} , p^{17} , p^{18} and p^{19} 65 are formed in the ends of the plate to receive mounting screws on the frame of the switch board. With regard to the functions of the 70 openings, p^7 receives the one hundred point switch S , p^8 receives a rotary distributing switch S' (used for selective ringing, auto-

matic release, etc.) comprising a single bank and a spindle rotated only by a single magnet unit s^{20} , similar in every respect to those in the larger switch; the openings p^{11} and p^{12} receive relays R , R' , R^2 , R^3 of Fig. 75 $\frac{1}{2}$; while the openings p^{13} , p^{14} and p^{15} permit the passage to the rear of the plate of the wiring terminals of the switch jack J , and of the connecting and testing rack T .

Referring to Figs. 4 and 5, it will be observed that the switch S' has its frame s^0 provided with lugs or ears for attachment to the posts p^4 , p^5 , p^6 in a manner similar to that described with regard to the switch S . Its contact bank s^{40} is secured by means of 80 corresponding ears to the rear ends of the same posts, whereby the alinement of its parts is also maintained with regard to any possible spring or warping in the plate P . The attachment of the switch frames s and s^0 however tends to prevent any distortion of the plate, by diagonal as well as transverse stiffening. These frames being made of 85 castings and being braced as the drawings show in all directions, stiffen the plate very 90 materially and the effect of this is distributed because they are secured in the one case at four points and in the other at three. As the plate is already stiffened longitudinally by the side ribs p^{20} , p^{21} , the net result is that 95 with the switches in place, the entire structure is adapted to resist relatively great shocks and strains without disturbance of any of the adjustments. It should be noted also that by assembling units and then 100 aggregations of units in this manner, carefully connecting those which have common adjustments either to each other or to the same fixed, interchangeable or removable parts, I secure absolute uniformity of operation and 105 interchangeability of parts. The relays R , R' , etc., are of a type described and claimed in my Patent No. 972,634, granted October 11, 1910, in which a return bar of soft iron is 110 bent over at both ends, one end r being attached to the plate P and the other end r' carrying the spool r^2 . The magnet core is shorter than the return bar and the armature r^3 is located in the space between the end of the core and the member r , passing 115 upward through the return bar under the spring mounting r^4 and bent at right angles to form an extended lever r^5 which underlies the springs and at its outer extremity carries an insulating stud r^6 to work the 120 springs. While the structure of this relay forms in itself the subject matter of the other application referred to, yet its structure is especially designed for use in the manner 125 herein disclosed, and I shall therefore claim this combination of elements. By reference to Fig. 1 it will be seen that the openings p^{11} , p^{12} , punched in the plate P , are positioned and proportioned correctly to receive and 130 inclose the insulated mounting r^4 of the re-

lay springs, while the screw holes p^{110} and p^{112} are located beneath these in proper position to receive the screws for securing the members r to the plate. The advantage in this arrangement is that all wiring for the entire plate may be completed symmetrically and harmoniously on the back of the plate P where the relay springs terminate and magnet terminals r^{50} all appear, as well as the bank contacts s^{40} , s^4 , and s^5 the jack terminals j^2 and the test or disconnecting terminals t^2 . On the other hand, everything that is required for adjustment or manipulation in the ordinary operation of an exchange is located on the front of the plate. This includes the adjusting screws for the relay cores, the open ends of the relay springs, the working parts of both switches S' and S (which are moreover susceptible of removal without disturbing the bank contacts or the wiring), and the testing terminals or miniature knife blade switches in the bank T . The circuits employed with this apparatus are now well understood in the art, and are commonly known as "automanual" circuits. My invention may also be used in full automatic circuits, as will be evident at once to those skilled in the art.

Figs. 6 and 7 show what I call my primary and first selector plate. The switches S^2 and S^3 mounted on this plate are the same in design as the switch S already described, but their functions are different. I have shown one contact bank of each of these switches removed in order to show the wipers w^2 and w^3 projecting through the plate, but these switches are both essentially testing switches, that is to say the primary selector switch S^2 contains in its banks the terminals of line circuits, with which it effects connection in response to calls over the lines for the purpose of connecting them with a local trunk circuit extending to the companion switch S^3 . The terminal rack T' and jacks J' , J^2 are located in the same relative positions on this plate as on the connector plate, but no distributing switch S' is required, a pair of condensers C , C' is mounted between the switches, and there are three rows of relays R' instead of two as on the connector plate. A point to be noted in Figs. 6 and 7 is the extension of the plate P' below the side flanges p^{21} and p^{20} . The reason for this is that the tools for making these flanges or ribs are standard, and the stiffening effect of the lower switch S^3 which extends from a point above the lower ends of the ribs to a point considerably below them, is such as to render the lower portion of the plate perfectly rigid in itself. The tools for forming the openings p^7 are standard and also those for the openings p^9 , p^{10} , p^{11} , p^{12} , p^{110} , p^{112} , p^{13} , p^{14} , p^{15} , p^{16} , p^{17} , p^{18} , and p^{19} . The posts p , p' etc. are also uniform on all

exception of the lengthening of the plate P' , with any structure it is standard.

Referring now to Figs. 8, 9 and 10, I have therein shown the manner in which these plates and the associated pieces of apparatus are mounted on a unit section for 100 lines. It should be understood that each of the plates P and P' in Figs. 5, 6, 7 and 8 is a single 100 line unit. In other words, if the plate of Fig. 4 were mounted in contiguity to the plate of Fig. 6, with proper line connections from the same group of 100 lines in multiple into the banks of the two switches S and S^2 , and trunk connections from the trunks of the switch S^3 to the wipers of the switch S , any one of the 100 lines could call in and obtain connection with the switch S^2 (assuming it to be idle), thence obtain control of the first selector switch S^3 , through its agency pick out the switch S , and then through the agency of that switch select the wanted line in the same group, connect therewith, and call up the subscriber thereon. In practice however this would obviously be an incomplete arrangement because only one line at a time could be used for conversation, and as the usual percentage of connecting apparatus is ten, I assemble ten pairs of plates of this kind as best shown in Fig. 8, the connector plates P being located above, and the primary and first selector plates P' being located below. The unit section frame F comprises the vertical angle irons f , carrying the horizontal members f^1 , f^2 , f^3 , f^4 , f^5 , f^6 , f^7 , f^8 and f^9 . It will be observed that an open space f^{10} is left at the top of the frame and this is because the frame is designed to take another row of plates P , which however would be selector plates and would be located in place of the connector plates now shown, the latter being moved up into the present vacant space. The several plates are supported by screws tapped to the several horizontal members f^1 , f^2 , f^3 , etc., lying in the notches p^{16} , p^{17} , p^{18} and p^{19} . Thus each plate is detachable as a unit without disturbing any of the other plates but of course in order to detach it the wiring on the back must be severed from the cable ends. The lowest five horizontal members marked f^5 to f^9 inclusive, carry the line and cut-off relays R' of the respective lines. It will be noted that each of these strips has twenty relays to the right and twenty-two to the left, the two left hand end relays in each case are group relays, and the other twenty are individual relays. One of the group relays is provided for each ten lines, being connected in the ground or battery return from the corresponding ten line relays. The purpose of these group relays is to close the starting circuit of the primary selector switch, also to raise the potential of their own "row" contacts in the several primary

selector banks containing multiples of their line groups. This will appear more fully from an examination of the circuits.

Further pieces of apparatus shown in Fig. 8 are the fuses and alarm relays on a panel at the left of the line and cut-off relays; also a double row of group line signal lamps, controlled by the group line relays, and which are marked G. Above these is a plate of similar dimensions to the plates P', carrying three switches similar in every way to the switch S' in Fig. 6, and which I preferably denominate distributing switches. The first of these S' is the distributing switch for the operator's key sets, which determines the idle key set switch to be started in response to a call. The next switch S' is a kick-off switch, controlled by a relay responsive to the last impulse sent after a complete cycle of selective impulses from the operator's sending machine, and under normal conditions removed from said control prior to said last impulse, by another relay energized in the normal position of the trunk switches. Under abnormal conditions however, as for example when a trunk whose primary selector S' has connected with a calling line, contains defective or inoperative pieces of apparatus which fail to respond and make the connection desired, then at the expiration of one complete cycle of the sending machine, the last impulse previously referred to will actuate the kick-off switch which will transfer the starting wire and the call to the next idle trunk whose primary selector switch S' will start immediately to find the calling line. This prevents a bad trunk from hanging up a calling line more than a few seconds.

Below the kick-off switch is the primary distributing switch S', which is common to a group of 100 lines as are its two associated switches. This responds to current in any of its groups of lines and selects the first idle trunk whose primary selector switch S' will then pick up the first calling line, and so on.

Mounted above the distributing switches at the left of the row of plates P, is a plate P' on which are four generator lamps g' to g' inclusive.

The operator's listening and impulse sending trunks, battery feed, common ground return, ringing current, busy back, etc., enter through the floor bushing E at the left and are protected from mechanical injury by the box e from whence they are distributed to the various relays and switches. Mounted on the top of this box is the alarm lamp A of that section.

At the rear and on either side of the frame are vertical rows of terminal blocks B B' and above them lying transversely of the frame are the cable runs of the line trunks and local trunks L L' supported in

brackets L' respectively. The line wires terminate in the blocks B, and are distributed therefrom to the bank contacts of the switches, while the blocks B' receive the terminals of the local trunks and effect the multiple connections between the switches of the different sections.

Having thus described my invention what I claim and desire to secure by Letters Patent is—

1. In a telephone exchange system, multiple unit sections arranged in predetermined order, each section including unit interchangeable groups of apparatus, each group including a plurality of interchangeable automatically operating electrical selective switching units of different order, and suitable connections between the several sections, between the several groups of each section, and between the several units of each group.

2. In a telephone exchange system, switch board frames, a unit section carried by each frame, each unit section including unit interchangeable groups of apparatus, each group including a plurality of interchangeable automatically operating electrical selective switching units of different order, and suitable connections between the several sections, between the several groups of each section, and between the several units of each group.

3. In a telephone exchange system, a unit section comprising multiple unitary interchangeable groups of apparatus mounted upon separate detachable plates, each group including interchangeable automatically operating electrical selective switching units of different order, and suitable connections between the groups and between the units of each group.

4. In a telephone exchange system, an interchangeable unit of apparatus, comprising a rectangular base plate having means for securing it to a support, and detachable interchangeable automatically operating devices including all the switches and relays pertaining to a single trunk mounted on said plate within the perimeter thereof whereby a plurality of said plates may be assembled side by side to constitute a board of substantially unbroken area.

5. In a telephone exchange system, a unitary interchangeable group of apparatus, comprising a perforated base plate having means for securing it to a support, automatic switch and relay mechanisms detachably mounted on said plate, the actuating elements of said mechanisms being secured to the front of said plate and the terminal contact elements being disposed to the rear of said plate.

6. A unitary interchangeable apparatus group for telephone exchange systems, comprising a base plate having means to attach

- it to a support, said plate having openings therein, and automatic switching mechanism including magnet actuating means and banked contacts mounted on the front and 5 rear faces of the plate respectively and wiping contacts extending through the plate.
7. A unitary interchangeable apparatus group for telephone exchange systems, comprising a base plate having means to attach it to a support, said plate having openings therein, automatic switching mechanism including magnet actuating means and banked contacts mounted on the front and rear 10 faces of the plate respectively and wiping contacts extending through the plate, and relays mounted on the front of said plates and having the contact terminals extending through adjacent openings and to the rear 15 of the plate.
8. A support for a unitary apparatus group for telephone exchange systems, comprising a metal plate having openings through which attached apparatus may extend and perforated studs or posts adjacent certain of said openings adapted to support certain of such apparatus.
9. A support for a unitary apparatus group for telephone exchange systems comprising a substantially rectangular metal plate having reinforcing ribs near its longitudinal edges, recesses at its ends for securing it in place, openings disposed over its area and posts adjacent certain of said openings to support certain of such apparatus.
10. As an article of manufacture a supporting unit base, an automatically operating selector switch detachably mounted on said base and comprising a frame and fixed 25 and movable elements, associated control relays for said switch also mounted on said base, operating circuit connections between the several relays and the switch, and terminal connections for the said circuit and apparatus.
11. As an article of manufacture a detachable supporting unit base member, a pair of permanently associated automatically operating self-contained selector 30 switches mounted on said member, individual trunk circuit connections run between them, and connective terminals associated therewith.
12. As an article of manufacture a detachable supporting unit base member, two automatically operating self-contained selector switches on said member, trunk circuit connections between them, control relays for the switches mounted on said base independently of said selective switches, together with operating connections run to the switches and relays and the trunk connections.
13. In a telephone exchange system, a unitary group of apparatus comprising a rectangular base plate having means for securing it to a support and automatically operating devices including switches and relays mounted on said plate within the perimeter thereof whereby a plurality of said 40 plates may be assembled side by side to constitute a board of substantially unbroken area.
14. In a telephone exchange system a plurality of multiple unit sections each complete for calls between a determinate number of lines, and each section comprising a number of unit groups arranged side by side, each group comprising in turn a connector, a primary selector, and a first selector arranged in rectilinear order, each group and each unit of each group being interchangeable, transversely arranged multiple connections between the connectors and primary selectors of the groups, longitudinal trunk connections between the primary selectors and first selectors on the one hand and between the first selectors and connectors on the other, and trunk connections between the connectors of all the boards and the first selectors of each board.
- In testimony whereof I affix my signature in presence of two witnesses.

CHARLES H. NORTH.
